UNITED STATES PATENT OFFICE.

ALEXANDER H. HANDLAN, JR., OF ST. LOUIS, MISSOURI.

LIFTING-JACK.

SPECIFICATION forming part of Letters Patent No. 313,935, dated March 17, 1885.

Application filed December 9, 1884. (No model.)

To all whom it may concern:

Be it known that I, ALEXANDER H. HANDLAN, Jr., of the city of St. Louis, in the State of Missouri, have invented a certain new and 5 useful Improvement in Lifting-Jacks, of which the following is a full, clear, and exact description, reference being had to the accompanying drawings, forming part of this specification, and in which—

10 Figure 1 is a front elevation of my improved jack. Fig. 2 is a side view. Fig. 3 is a top view. Fig. 4 is a longitudinal section of the body taken on line 4 4, Fig. 3, showing the screw and plunger in side view. Fig. 5 is a 15 transverse section taken on line 5 5, Fig. 4.

My invention relates to those lifting-jacks having a register to indicate the amount lifted; and my invention consists in the construction 20 fully described hereinafter, and pointed out 25 in the claims.

Referring to the drawings, A represents the body, and B the screw, of a lifting-jack. The former is hollow and acts as a cylinder to a 25 plunger or piston, C, that fits snugly therein, and with which the screw has threaded connection.

D represents a register, of any well known form or construction, and I a port or passage-way forming a communication between the 30 register and the lower part of the cylinder or

body of the jack, which is supplied with a suitable liquid, as shown in Fig. 4. The port is preferably provided with a valve, J.

When the jack is used, the plunger is forced downward, displacing the liquid beneath it by 35 forcing it through the port or passage-way into the register, and thus the amount lifted or the strain brought to bear upon the jack is indicated by the register.

By removing the cap L of the body, the 40 plunger may be taken out to supply the liquid; or the liquid may be supplied by removing a screw-plug, O. (See Fig. 4.) The plunger has a packing, M, on its lower end.

I claim as my invention—
1. In a lifting-jack, the combination of the 45 body, screw, plunger, and register, the latter being connected to the former by means of a port for the passage of liquid displaced by the plunger, substantially as set forth.

2. The combination of a lifting-jack and 50 register, arranged as described, that the latter will indicate the amount lifted by the former through means of liquid forced from the former to the latter, as specified.

ALEXANDER H. HANDLAN, JR.
